(57) **CLAIM**

The ornamental design for a tablet case, as shown and described.

DESCRIPTION

FIG. 1 is a front perspective view of a tablet case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof;

FIG. 9 is a front perspective view of a tablet case in a detached status, shown separately to show aspects of the design not visible when combined;

FIG. 10 is a rear perspective view of a tablet case in a detached status, shown separately to show aspects of the design not visible when combined;

FIG. 11 is a front perspective view of a tablet case in a combined state of use;

FIG. 12 is a front perspective view of a tablet case in another combined state of use;

FIG. 13 is a front perspective view of a tablet case of FIG. 1, where in the lid of the tablet case is folded up; and,

FIG. 14 is a rear perspective view of a tablet case of FIG. 1, where in the lid of the tablet case is folded up.

The broken lines in the drawings illustrate the portions of the tablet case, which form no part of the claimed design.

1 Claim, 14 Drawing Sheets
